UNITED STATES PATENT OFFICE.

CATO HAARBERG, OF CHICAGO, ILLINOIS.

PACKAGE CARRIER.

Application filed July 19, 1924. Serial No. 727,054.

To all whom it may concern:

Be it known that I, CATO HAARBERG, a citizen of the United States of America, and a resident of Chicago, in the county of Cook and State of Illinois, have invented a new and Improved Package Carrier, of which the following is a description.

My invention relates to a carrier for boxes and other packages, and particularly to that type of carrier involving two carrier bars so that the package can be carried by two persons in tandem and gripping the ends of the bars.

The general object of my invention is to provide a device of the indicated character improved in various particulars especially with respect to means whereby the persons carrying the package may cause the package to be firmly gripped at the sides by manipulation of the carrier bars.

More specifically, the invention has for an object to provide a device of the indicated purpose having increased efficiency and characterized by simplicity of construction as well as convenience of manipulation and control to grip or release the package.

The nature of my invention and its distinguishing features and advantages will clearly appear as the description proceeds.

Reference is to be had to the accompanying drawings forming a part of this specification, it being understood that the drawings are merely illustrative of practical examples of the invention.

Figure 1 is a plan view of a package carrier embodying my invention showing the same applied to a packing case for the carrying of the same;

Figure 2 is a fragmentary end view on an enlarged scale of a portion of the carrier showing one of the carrier bars and a portion of the flexible connection between the bars before the device is disposed in gripping relation to the packing case shown in part;

Figure 3 is a view similar to Figure 2 on the same enlarged scale but showing the parts in said Figure 2 disposed in a manner to cause the package to be gripped;

Figure 4 is a fragmentary plan view on about the scale of Figure 1 showing an end portion of one of the bars and illustrating a modified hand-hold element.

Figure 5 is a view similar to Figure 4

showing a further modified form of the invention.

In carrying out my invention in accordance with the illustrated example, two longitudinal carrier bars 10 are provided, adapted to be disposed at each side of a packing case A or other package to be carried. On each end of each bar is provided a turnable sleeve 11, which may have a suitable formation to enable a firm grip to be taken by those carrying the device, and of a character to be engaged by the thumb or finger for turning the sleeves.

In the form shown in Figures 1 to 3, each sleeve 11 is formed with diametrically opposite thumb pieces 12 directed radially outward sufficiently distant from the end of the sleeve to afford an end cylindrical portion so that two handles at one end may be readily grasped by the persons carrying the package and with the lateral thumb members 12 disposed for one of the thumbs of each hand to engage a member 12 as indicated by dot-and-dash lines in Figure 3 for turning the sleeves on the rod 10.

Those sleeves at the corresponding ends of the two bars 10 are connected in pairs by a transverse flexible element such as a chain 13. Each sleeve 11 adjacent to that end opposite to that to be grasped is formed with an annular series of radially disposed spurs 14.

With the described construction when the thumbs of the persons to carry the package are pressed against one of the members 12 for turning the sleeves 11 in a direction to wind up the chains 13 and thereby draw the bars 10 toward each other so that the spurs 14 will engage the sides of the box or other package A.

The chains 13 are adapted to be adjusted to vary their total lengths to suit boxes or other packages of various widths. In the illustrated example one end of each chain is adapted to have a link thereof engaged with a snaphook 15 which is held to the adjacent sleeve 11 by a link 16 connected with a rigid loop 17 on the sleeve.

It will be observed from the foregoing that an approximate adjustment of the distance between the two side bars 10 is produced by adjusting the length of the chains 13 and that an additional drawing of the bars 10 with their sleeves 11 toward each

other is effected by turning the sleeves on said bars, the final adjustment effecting gripping engagement of the spurs 14 or other gripping members provided on the sleeves with the sides of the package. Indeed, it will be clear that by turning the sleeves 11 sufficiently to wind up the chains 13 to a material extent, any adjustment of the distance between the bars may be effected within the limits of the lengths of the chains 13.

In the form shown in Figure 4 a part of a box A is indicated as in the other figures and the modification includes the same bars 10, chains 13 and the spurs 14, said spurs being employed as the preferred form of gripping means. In Figure 4, however, the sleeve designated 111 and corresponding generally with the sleeves 11 instead of being provided with the diametrically opposite thumb pieces 12, is provided with an offset handle 112 which may be disposed at the outer side of the sleeve or side remote from the package A and as said offset handle 112 of a pair of sleeves 111 is grasped, the sleeves will be automatically turned to wind up the chains (13) and engage the spurs 14 with the sides of the package.

In the form shown in Figure 5 the spurs, 114, are directly on the bar 110, also the offset handle 212 is integral with the bar 110 and the chains, one of which is indicated, are connected directly at the ends thereof with said bar 110.

I would state in conclusion that while the illustrated examples constitute practical embodiments of my invention, I do not limit myself strictly to the exact details herein illustrated, since, manifestly, the same can be considerably varied without departure from the spirit of the invention as defined in the appended claims.

Having thus described my invention, I claim:

1. A package carrier comprising a pair of bars adapted to be disposed at the opposite sides of the packages, sleeves turnable on said bars at the ends thereof, said sleeves affording a zone adapted to be grasped by the hands of the persons using the carrier, means on the sleeves to be engaged by the hand grasping the sleeves to turn the sleeves on the rods, means on the sleeves adapted to engage and grip the sides of the package, and flexible elements connecting the sleeves at the corresponding ends

of the bars, so that the turning of the sleeves on the bars will wind or unwind said flexible elements.

2. A package carrier comprising bars adapted to be disposed at opposite sides of a package, transverse flexible elements disposed between the bars, and means to cause winding up of said flexible elements in convolutions disposed about the axes of the bars.

3. A package carrier comprising bars adapted to be disposed at opposite sides of a package, sleeves turnable on the bars at each end and adapted to be grasped, and flexible elements extending transversely between and secured to said sleeves to wind thereon by the turning of the sleeves.

4. A package carrier comprising bars adapted to be disposed at opposite sides of a package, transverse flexible elements disposed between the bars, and means to cause winding up of said flexible elements in convolutions disposed about the axes of the bars, together with means to automatically grip the package with the winding of the chains and the shortening of the distance between the sides.

5. A package carrier comprising bars adapted to be disposed at opposite sides of the package, gripping means directly on the bars, transverse flexible elements disposed between the bars, and means to cause winding up of said flexible elements in convolutions disposed about the axes of the bars.

6. A package carrier comprising bars adapted to be disposed at opposite sides of a package, sleeves turnable on the bars at each end and adapted to be grasped, and flexible elements extending transversely between and secured to said sleeves to wind thereon by the turning of the sleeves, together with means on the sleeves adapted to be engaged by the hands of the users of the carrier for bringing about the turning movement of the sleeves.

7. A package carrier comprising longitudinal bars adapted to be disposed at opposite sides of the package, sleeves turnable on the bars at each end and adapted to be grasped, means on the sleeves adapted to be engaged by the hands for turning the sleeves, approximately radial spurs on the sleeves adapted to engage the package, and transverse flexible connections between the sleeves at the respective ends of the bars.

CATO HAARBERG.
